UNITED STATES PATENT OFFICE.

CHESTER W. BENJAMIN, OF LAKWOOD, OHIO, ASSIGNOR TO THE WELLMAN-SEAVIER-MORGAN COMPANY, OF CLEVELAND, OHIO, A CORPORATION OF OHIO.

MANIPULATOR FOR ROLLING MILLS.

Application filed August 17, 1918. Serial No. 250,377.

To all whom it may concern:

Be it known that I, CHESTER W. BENJAMIN, a citizen of the United States, residing at Lakewood, in the county of Cuyahoga and 5 State of Ohio, have invented a certain new and useful Improvement in Manipulators for Rolling Mills, of which the following is a full, clear, and exact description.

This invention relates to a manipulator 10 for rolling mills and has for its chief object to provide a manipulator including side guards which are designed to be moved laterally over the feed table, together with turning bars which move with one of the guards 15 and are designed to turn the work on the rolls of the table, the whole being so constructed and arranged that the parts are readily accessible for repairs or replacement and are practically free from the effects of 20 falling scale.

The further object is to so design the parts 25 of the manipulator that the guards can be moved laterally over the rolls and the turning bars or fingers actuated to turn the work without requiring that a heavy complicated mechanism be moved.

The still further object is to provide a manipulator with turning bars so supported 30 and operated that they are more effective than the prior devices for turning the work on the rolls.

Still further, the invention aims to provide in connection with the feed table of a rolling mill, a manipulator which is efficient 35 and durable as well as economical in design as far as materials and parts are concerned, and readily and easily controlled so that movements of desired extent and direction can be imparted.

40 The invention may be briefly summarized as consisting in certain novel details of construction and combinations and arrangements of parts which will be described in the specification and set forth in the appended claims.

In the accompanying sheets of drawings 45 wherein I have shown the preferred embodiment of my invention, Fig. 1 is a top plan view of a portion of the rolling mill showing the table at one side of the reducing rolls and the manipulator associated with the table and embodying my invention; Fig. 2 is a transverse sectional view; Fig. 3 is a

view looking toward the left of Fig. 1, the 55 squared ends of rock-shafts being in section, this view illustrating the manner in which the turning bars are actuated; Fig. 4 is a sectional view substantially along the line 4-4 of Fig. 1, looking in the direction indicated by the arrows; Fig. 5 is a sectional 60 view substantially along the line 5-5 of Fig. 1, looking in the direction indicated by the arrows; Fig. 6 is a detail view partly in section and partly in elevation showing particularly the turning bars, the latter being 65 shown by full lines in the lowermost position and by dotted lines in an elevated position to which they are moved in turning the work.

The rolling mill includes the usual reducing rolls, on each side of which is a feed table composed of a series of rolls 10 supported in the side frames 11 of the table and operated preferably by bevel gearing 12 in the customary manner. Only one of the two 75 feed tables is shown, it being understood that the table on the opposite side of the rolls will be like that here illustrated.

Arranged to move laterally over the rolls 80 10 of the feed table, at right angles to the axes of the rolls, are two side guards 13 and 14, the chief function of which is to shift the work laterally on the feed rolls so as to position the work for the desired pass of the reducing rolls. These side guards are pref- 85 erably made heavy and rigid enough that they can be utilized to straighten the work should it be curved or bent by passing through the reducing rolls.

Each of the two guards is supported and 90 actuated by two horizontal arms or beams 15 serving as guides, which extend laterally outward from the corresponding side guard. The rear end of each of these guard-supporting arms 15 has rollers 16 which engage 95 flanges of a track beam here shown in the form of a casting 17, which is at the side of the table and extends laterally outward therefrom at right angles to the table. The forward portion of each guard-supporting 100 arm 15 carries a roller 18 (see Fig. 2), which travels over a track 19 formed at the top, a spacer 20 extending between the side frames 11 of the feed table, two of such tracks and spacers being utilized.

105 The guard-supporting arms 15 are moved

back and forth so as to shift the guards laterally over the rolls of the table by motor actuated rack and pinion mechanism, including pinions 21 engaging rack teeth 22 on the lower faces of the guard-supporting arms 15. The pinions at each side of the table are fixed to a shaft 23, suitably journaled in bearings supported by the castings 17 (see Figs. 1 and 2). In this instance each 10 shaft 23 is rotated through reducing gearing 24 by a counter-shaft 25, which through reducing gearing 26 is driven by a stationary motor 27, which is preferably an electric motor, although a motor of any other suitable type may be employed, and in fact, other means of rotating the shafts 23 may be utilized.

Each side guard is actuated in precisely the same manner and by the mechanism described, the same reference characters being utilized and the same description applying to similar and corresponding parts on both sides of the table, it being understood also that the two guards of the table are similarly supported as well as actuated.

It was heretofore stated that a table similar to that shown would be provided at the opposite side of the reducing rolls 10, which table will be provided with side guards 30 similar to the guards 13 and 14. In practice it is desirable that the guard at one side of one table and the corresponding guard at the same side of the opposite table be maintained in alignment and actuated in unison through the same motor. To that end each shaft 23 is connected to a similar shaft extending along the table on the opposite side of the reducing rolls. The manner in which this is preferably done is shown in Figs. 4 and 5, which show the shaft 23 connected by a pair of pinions 28 to a lower shaft 29 (see also Fig. 1), which will be connected by pinions similar to 28 to a shaft similar to and in alignment with shaft 23 and designed to be provided with pinions to operate the guard in alignment with the guard 13 or 14, as the case may be.

Thus it will be understood that by operating the motors 27 either singly or in unison the two guards of each table will be moved back and forth over the rolls to position the work for the desired pass of the rolls and to straighten the work if it becomes necessary.

In addition to shifting the work laterally on the rolls by the guards above described it is customary to provide one of the guards of a table at one side of the reducing rolls (or one of the guards of each of the tables 60 if it is desired to turn the work at each side of the reducing rolls) with turning bars or equivalent devices for turning the work through an arc of 90°. The mechanism which I provide for this purpose and which 65 is here shown associated with the guard

14 constitutes an important part of the present invention, it being understood that work turning means such as here shown, may be provided on one or both sides of the reducing rolls as circumstances require. 70

To turn the work on the rolls of the table I provide a series of turning bars 30 which are designed to be moved in vertical planes in grooves on the front face of guard 14, and each of which is provided with a 75 shoulder 30a which is normally beneath the top line of the rolls of the feed table, these bars being designed to be elevated so that the shoulders will engage beneath the work in the manner as shown in Fig. 2, and turn 80 it as illustrated in that figure, the turning bars being shown in Fig. 2 in about their middle position.

The manner in which these turning bars are mounted and actuated is of considerable 85 importance, these bars, in accordance with my invention, being supported or suspended by a series of upper arms 31 pivotally connected to the upper ends of the turning bars and by a series of lower arms 32 pivoted to 90 the lower ends of the turning bars. The outer ends of the series of upper arms 31 are separately pivoted at 33 to brackets or the like mounted on a cross arm 34 extending between and secured to the two arms 15 95 which support the guard 14, this cross arm 34 being parallel to and at the rear of the guard 14 and, of course, moving inwardly and outwardly with the guard. The outer ends of the series of lower arms 32 are 100 separately pivoted at 35 to the lower side of this cross arm 34.

The turning bars 30 are raised and lowered by a horizontal bar 36 which is just beneath the upper series of arms 31 and is designed 105 to be raised and lowered so as to lift the arms 31 or lower them and when raised and lowered moving in parallelism. For this purpose the ends of the bar 36 are pivotally connected to arms 37 secured to the forward 110 or inner ends of two rock-shafts 38 and 39 which are parallel to and directly above the arms 15 which support the side guard 14. These rock-shafts 38 and 39 are journaled in bearings 40 carried by these guard supporting arms 15 and move inwardly and outwardly with the latter, and their rear ends 38a and 39a which are squared are slidingly supported by stationary bearings 40a supported at the outer ends of the beds or castings 115 120 125 130 135 140 145 150 155 160 165 170 175 180 185 190 195 200 205 210 215 220 225 230 porting the guard 14. This shaft has a crank 45 which is connected by a rod 46 to the lower part 47 of a double armed crank whose hub or middle portion receives with a 5 sliding fit, the outer squared part 38^a of the rock-shaft 38, this double armed lever being held from movement longitudinally with the rock-shaft 38 but rocking or rotating the same as will be subsequently explained.

10 The upper part 48 of the double armed lever is connected by a diagonally extending rod 49 to an arm or lever 50 similar to and parallel with the lower arm or part 47 of the double armed lever. This arm or lever 15 50 has a hub with a squared opening which receives with a sliding fit the outer squared end 39^a of the rock-shaft 39.

Thus both rock-shafts 38 and 39 will travel with the side guard 14 and arms which support and actuate the same, and in so doing are guided through the double armed lever 47, 48 and the lever 50, but when it is desired to turn the work on the feed table through the motor 40 and the described 25 mechanism the two rock-shafts will be turned simultaneously in opposite directions and equal amounts, elevating the arms 37 at the forward ends to these rock-shafts and lifting the bar 36 whose ends have a pin 30 and slot connection with the said arms 37 so that when the arms 37 are elevated the bar 36 will move upwardly freely. The continuous rotation of the crank results in the lowering of the bar 36 following the elevating 35 of the same. When the bar 36 is elevated in the manner described, it engages and lifts the upper series of arms 31 connected to the upper ends of the turning bars 30, in consequence of which the turning bars 30 are 40 swung upwardly and inwardly slightly. This inward movement of the turning bars combined with the upward movement, is of considerable importance, for it prevents the turning bars sliding off the lower corner of 45 the work while in the act of turning it. Similarly, when the turning bars are lowered by the mechanism described, they swing downwardly and outwardly to the full line position shown in Fig. 6. When in this position, the shoulders 30^a are above the top of 50 the feed rollers and the upper reduced portions of the turning bars are back of the front face of the guard 14.

As here shown, the lower series of arms 55 32 are of approximately the same length as the upper series of arms 31, so that a figure formed by the pivotal points of the arms 31 and 32 forms an approximate parallelogram, though this is not necessary to the 60 operation of the mechanism.

Not only are the turning bars given a movement which is admirably adapted to turn the work on the feed table, for the reason explained, but that part of the mechanism 65 which actuates the turning bars and

which moves forwardly and rearwardly with the guard, is much lighter in weight though none the less effective than the major portion of the manipulators in use at the present time, and in this respect also, my 70 improved manipulator has an important advantage over prior mechanism. Additionally the parts are so located that they are not affected by falling scale and can be readily reached and repaired or replaced 75 with other parts, if necessary.

I do not desire to be confined to the exact details shown, but aim in my claims to cover all modifications coming within the scope of the following claims. 80

Having described my invention, I claim:

1. In combination with the feed table of a rolling mill, a manipulator including a side guard adapted to be moved laterally over the feed table, a plurality of turning bars for turning the work on the feed table, said turning bars being mounted for endwise movement in vertical planes, and means for imparting to the upper and lower portions of each of the turning bars a positive upward and inward movement and a positive outward movement when lowering. 90

2. In combination with the feed table of a rolling mill, a guard movable laterally over the feed table, a plurality of turning bars adapted to turn the work on the table, and two sets of swinging arms supporting each of said turning bars. 95

3. In combination with the feed table of a rolling mill, a plurality of turning bars adapted to turn the work on the table, two sets of swinging arms supporting each of said turning bars, and means for swinging said arms to impart to the turning bars an upward and inward movement in turning 100 the work, and a downward and outward movement to normal position. 105

4. In combination with the feed table of a rolling mill, turning bars for turning the work on the table, and means for supporting 110 said turning bars comprising upper and lower sets of swinging arms connected respectively to the upper and lower portions of each of the turning bars.

5. In combination with the feed table of a rolling mill, turning bars for turning the work on the table, means for supporting said turning bars comprising upper and lower sets of swinging arms connected respectively to the upper and lower portions of each of the turning bars, and means for actuating the upper set of arms to elevate the turning bars. 115

6. In combination with the feed table of a rolling mill, a guard movable laterally 125 over the feed table, supporting guides for the guard extending laterally outward from the feed table, turning bars movable laterally with the guard and adapted to be elevated to turn the work on the table, means mounted 130

on the guides at the rear of of the guard for supporting the turning bars, and means for actuating the turning bars.

7. In combination with the feed table of a rolling mill, a guard movable laterally over the feed table, supporting guides for the guard extending laterally outward from the feed table, turning bars movable laterally with the guard and adapted to be elevated to turn the work on the table, means mounted on the guides at the rear of the guard and independently thereof for supporting the turning bars, and devices movable with the guides for actuating the turning bars.

8. In combination with the feed table of a rolling mill having laterally movable guards, guides extending laterally outward from the table and supporting the guards, turning bars movable with one of the guards, an upper set and a lower set of arms pivotally supported by the guides and connected respectively to the upper and lower portions of each of the turning bars and means for positively turning one set of the arms.

9. In combination with the feed table of a rolling mill having laterally movable guards, guides extending laterally outward from the table and supporting the guards, turning bars movable with one of the guards, an upper set and a lower set of arms pivotally supported by the guides and connected respectively to the upper and lower portions of each of the turning bars, and means movable with the guides of said guard and independent of the latter for actuating the lifting bars.

10. In combination with the feed table of a rolling mill, a guard movable laterally over the table, guides supporting the guard and extending laterally outward from the table, turning bars for turning the work on the table movable laterally with the guard, and means for elevating the turning bars comprising a rock-shaft at right angles to the guard and operatively connected with the turning bars.

11. In combination with the feed table of a rolling mill, a guard movable laterally over the table, guides supporting the guard and extending laterally outward from the table, turning bars for turning the work on the table movable laterally with the guard, and means for elevating the turning bars comprising a rock-shaft associated with one of the guides and extending longitudinally thereof, said rock-shaft being operatively connected with the turning bars to elevate or lower the same.

12. In combination with the feed table of a rolling mill, a guard movable laterally over the table, guides supporting the guard and extending laterally outward from the table, turning bars for turning the work on the table movable laterally with the guard,

means for elevating the turning bars comprising a rock-shaft movable with one of the guides and extending longitudinally thereof, said rock-shaft being operatively connected with the turning bars to elevate or lower the same, and means having a sliding connection with the rear portion of the rock-shaft for rocking the same.

13. In combination with the feed table of a rolling mill, a guard movable laterally over the table, guides projecting laterally outward from the table, turning bars movable with the guard and supported for movement in vertical planes at the front thereof to turn the work, and means for elevating and lowering the turning bars comprising a pair of rock-shafts extending longitudinally of the guides and movable therewith, said rock-shafts being operatively connected with the turning bars to shift the same.

14. In combination with the feed table of a rolling mill, a guard movable laterally over the table, guides projecting laterally outward from the table, turning bars movable with the guard and supported for movement in vertical planes at the front thereof to turn the work, means for elevating and lowering the turning bars comprising a pair of rock-shafts extending longitudinally of the guides and movable therewith, said rock-shafts being operatively connected with the turning bars to shift the same, and a motor connected to the rock-shafts to simultaneously rock the same.

15. In combination with the feed table of a rolling mill, a guard movable laterally over the table, guides for said guard projecting laterally outward from the table, turning bars movable with the guard and supported for movement in vertical planes at the front thereof to turn the work, means for elevating and lowering the turning bars comprising a pair of rock-shafts extending longitudinally of the guides and movable therewith, said rock-shafts being operatively connected with the turning bars to shift the same, and a stationary motor having operative connections with both rock-shafts, said connections being slidingly related to the rock-shafts so that the latter may move forwardly and rearwardly with respect thereto.

16. In combination with the feed table of a rolling mill, a guard movable laterally over the feed table, guides projecting laterally outward from the guard and supporting the same, turning bars movable laterally with the guard and adapted to be elevated at the front of said guard, arms pivotally connected to the turning bars and pivotally supported at the rear of the guard, a bar extending beneath said arms for raising and lowering the same, and means for moving said bar vertically.

17. In combination with the feed table of a rolling mill, a guard movable laterally

over the feed table, guides projecting laterally outward from the guard and supporting the same, turning bars movable laterally with the guard and adapted to be elevated 5 at the front of said guard, arms pivotally connected to the turning bars and pivotally supported at the rear of the guard, a bar extending beneath said arms for raising and lowering the same, and means connected to 10 the ends of said bar for raising and lowering it.

18. In combination with the feed table of a rolling mill, a guard movable laterally over the feed table, guides projecting laterally outward from the guard and support- 15

ing the same, turning bars movable laterally with the guard and adapted to be elevated at the front of said guard, arms pivotally connected with the turning bars and pivotally supported by the guides at the rear 20 of the guard, a bar extending beneath said arms for raising and lowering the same, a pair of rock-shafts extending parallel to the guides and connected to the ends of said bar to raise and lower it, and means for 25 rocking the rock-shafts.

In testimony whereof, I hereunto affix my signature.

CHESTER W. BENJAMIN.
